(57) **CLAIM**

The ornamental design for a tray for railing attachment device, as shown and described.

DESCRIPTION

FIG. 1 is a top perspective view of a tray for railing attachment device showing our new design;

FIG. 2 is a bottom perspective view thereof;

FIG. 3 is a front elevation thereof, the side opposite being a mirror image;

FIG. 4 is a right side elevation thereof, the side opposite being a mirror image; and,

FIG. 5 is a top plan view thereof; and,

FIG. 6 is a bottom plan view thereof.

The broken line showing of environment is for illustrative purposes only and forms no part of the claimed design.
